UNITED STATES PATENT OFFICE.

GEORGE S. DEFFENBAUGH, OF WOODMEN, COLORADO.

DESIGN FOR A PAPER WEIGHT OR SIMILAR ARTICLE.

Application filed February 18, 1928. Serial No. 25,487. Term of patent 7 years.

To all whom it may concern:

Be it known that I, GEORGE S. DEFFENBAUGH, a citizen of the United States of America, residing at Woodmen, in the county of El Paso and State of Colorado, have invented a new, original, and ornamental Design for a Paper Weight or Similar Article, of which the following is a specification, reference being had to the accompanying drawing, forming a part hereof.

In the drawing:

Figure 1 is a front elevation of a paper weight showing my design;

Fig. 2 is a side elevation of the same, and

Fig. 3 is a rear elevation thereof.

I claim:

The ornamental design for a paper weight or similar article, as shown.

GEORGE S. DEFFENBAUGH. [L.S.]
